Des. 222,398
Patented Oct. 19, 1971

222,398

PEDESTRIAN SIGNAL

John E. Roberts, 2198 Garden Drive,
Wickliffe, Ohio 44092

Filed July 8, 1970, Ser. No. 23,866

Term of patent 14 years

Int. Cl. D29—99

U.S. Cl. D72—1

FIG. 1 is a perspective view of a pedestrian signal embodying my new design;

FIG. 2 is a front elevational view thereof;

FIG. 3 is a top plan view thereof;

FIG. 4 is a side elevational view thereof.

I claim:

The ornamental design for a pedestrian signal, as shown.
